*Primary Examiner—Philip S. Hyder
Attorney, Agent, or Firm—Lowe Hauptman Gopstein & Berner*[57] **CLAIM**

The ornamental design for a transparent storage container with lid, as shown and described.

DESCRIPTION

FIG. 1 is a perspective view of a transparent storage container with lid according to my new design;
 FIG. 2 is a top plan view of the container of FIG. 1;
 FIG. 3 is a bottom plan view of the container of FIG. 1;
 FIG. 4 is a left side view of the container of FIG. 1;
 FIG. 5 is a right side elevation of the container of FIG. 1;
 FIG. 6 is a front elevation of the container of FIG. 1;
 FIG. 7 is a rear elevation of the container of FIG. 1;
 FIG. 8 is an exploded perspective view of the container body and lid according to my new design;
 FIG. 9 is a bottom view of the container body without the lid attached; and,
 FIG. 10 is a bottom view of the container lid.
